UNITED STATES PATENT OFFICE.

WILLIAM H. BEEHLER, OF BALTIMORE, MARYLAND.

ARTICLE-CARRYING BRIEF BAG.

Application filed June 25, 1927. Serial No. 201,333.

My invention relates to hand-bags, and especially to those of the class known as brief-bags, provided with improved and simplified means for conveniently securing and carrying an umbrella, parasol or other articles in a convenient and protected position therein.

Bags of this class usually have one or more pockets, a closure flap covering the open tops of the pockets, and straps connected to the closure flap or encircling the bag near each end, overlying the closure flap, provided with buckles, and held against lateral displacement by loops secured to front or rear faces of the bag.

15 The invention consists in providing article-receiving loops located at the inner face of the upper, or fold portion of the closure-flap, near the ends thereof; and preferably, as in the present specific embodiment, I provide 20 strap-slots in the stated portion of the closure-flap, and pass the brief bag straps through these slots, to form the interior loops, in which the umbrella, parasol or other article is inserted, is then enclosed and located in 25 protected position above the pockets when the flap is closed, and is secured against displacement by the act of tightening and buckling the straps, whereby the strap-loops are tightened about the article.

30 The accompanying drawing shows one representative embodiment of the invention, which is however capable of modifications, and I contemplate the employment of any structures that are within the scope of the 35 appended claims.

Fig. 1 is a front elevation of a brief bag embodying the invention in one form, in open position.

Fig. 2 is a similar view, showing the bag 40 closed, with a part of the closure flap broken away.

Fig. 3 is a section at 3—3 Fig. 2.

The brief bag, chosen as an illustration of an article of baggage readily adaptable for 45 carrying an umbrella, parasol or other article for the purposes of this invention, has the usual front and back walls 1 and 2 of leather or substitute material, with interposed pockets having intermediate walls or sheets and 50 end bellows formations, and a closure flap 3

which is usually integral with the back wall and comprises an upper portion 4 which is curved or folded over the tops of the pockets when in closed position and to which the handle 5 is connected. The flap terminates 55 in a portion which overlies the front wall of the bag and is provided at the center of its lower edge with a latch or hasp 12 to co-operate with a lock 13 secured to the front wall 1 as usual.

60 Straps 6 are also provided, encircling the bag near its ends and secured against lateral displacement by cross pieces forming strap-retaining loops 15 as usual. One end of each strap is provided with a buckle 7, and the 65 other end has spaced buckle-tongue holes 8. Otherwise, shorter straps may be employed, which do not encircle the bag.

For the purpose of detachably securing the umbrella or parasol or other article within the bag, spaced, laterally-directed slots 9 are cut in the upper portion 4 of the closure flap in the normal planes of the straps, and the straps are passed inwardly through the rearward slots 4 and again outwardly 75 through the forward slots, thus forming strap loops 10 interior to the closure flap. In case short straps are used, they may be secured by rivets to upper portions of the rear wall 2, near the rear slots 9, and passed 80 through the slots in the manner above explained, or they may be secured to the inner face of the closure and passed out through the forward slots 9.

The umbrella or parasol U, chosen as an example of an article well-adapted for carrying in the bag, is of a length suitable for a brief bag of ordinary dimensions, and is preferably of a type having a short, blunt-ended tip T, inserted through the strap loops 90 10 when the closure flap is open. The fabric or cover portion C of the umbrella when closed is of such length that it is entirely or almost entirely comprised within the lengthwise dimension of the bag. Umbrellas suitable for this purpose also have a relatively short handle H, so that neither the tip nor handle end will project more than a few inches beyond the limits of the bag.

After the umbrella has been inserted 100

through the strap loops and positioned so that almost all of the cover fabric is within the lengthwise limits of the bag, (Fig. 1) the closure flap is dropped to closed position, whereupon the umbrella is located within the upper curved portion 4 of the closure flap and just above the pockets; and the free ends of the straps 6 are located as usual in bags of this type, ready for insertion in the 10 buckles, tightening and fastening whereupon the strap loops 10 are drawn with a desired degree of tightness about the umbrella cover fabric, and the bag at the same time is closed and supported by the straps, the lock members 12 and 13 being also usually engaged in the usual manner (Fig. 2).

In this way the umbrella is held so securely by the strap loops that it is practically immovable and the fabric is not subject to wear 20 occasioned by chafing against parts of the bag, and is also protected from external dust and dirt by the closure flap. The umbrella is immediately accessible for use by opening the closure flap and pulling the umbrella out 25 from the loops, whereupon the bag is again closed and the straps drawn tight to close and secure the closure flap in the usual way. To replace the umbrella in the bag it is only necessary to open the closure flap and pull 30 out the strap portions constituting the loops 10 sufficiently to reinsert the umbrella therein.

Desirably, stops in the form of studs or buttons 6^a are secured, as by riveting, to the straps, just forward of the front slots 9, these 35 stops being so located on the straps to provide strap portions of proper length to form the loops 10. These stops serve, when the closure flap is open, to prevent the straps from pulling back through the forward slots 9, 40 and so enlarging the loops as to permit the umbrella to slip or fall out of the bag.

Instead of an umbrella or parasol, other articles, such as rolls of drawings, gymnasium shoes, a rolled or folded rain-coat or cape, 45 or others too numerous to mention, may be secured in the loops, or either of them.

I have therefore provided in an ordinary article of hand luggage such as a brief bag, with very simple modifications involving almost negligible expense, means for conveniently and securely holding and enclosing therein in protected position, an umbrella or parasol, which is thus made immediately available for use as a protection against sun 55 or rain, and in such a way that when not in use the umbrella or like article is easily carried and does not occupy any of the bag space ordinarily available for carrying papers, books or other articles.

60 I claim:

1. A bag comprising front and rear walls, a closure flap extending from the rear wall and foldable over the upper portion of the bag and overlapping the front wall, the upper, 65 folded portion of the closure flap being

provided near each end with spaced, longitudinally-directed slots, and straps encircling the bag in the transverse planes of said slots, means securing the straps against lateral displacement, upper portions of the straps being 70 inserted through the rearward slots and emerging through the forward slots to form loops interior to the closure flap and adapted to receive and secure therein an umbrella or other article, the straps being provided with 75 buckles, whereby the closure flap may be secured in closed position in the usual manner and the article secured by the loops in enclosed position within the upper portion of the closure flap.

2. A bag comprising front and rear walls, a closure flap extending from the rear wall and foldable over the upper portion of the bag and overlapping the front wall, the upper, folded portion of the closure flap being 85 provided near each end with spaced, longitudinally-directed slots, and bag-closure straps in the transverse planes of said slots, upper portions of the straps being inserted through the rearward slots and emerging 90 through the forward slots to form loops interior to the closure flap and adapted to receive and secure therein an umbrella or other article, and means for securing end portions of the respective straps exteriorly to the bag front wall, whereby the closure flap may be secured in closed position in the usual manner and the article secured in the loops in enclosed position within the upper portion of the closure flap.

100 3. A bag comprising front and rear walls, a closure flap extending from the rear wall and foldable over the upper portion of the bag and overlapping the front wall, the upper, folded portion of the closure flap being provided near each end with spaced, longitudinally-directed slots, and bag-closure straps in the transverse planes of said slots, upper portions of the straps being inserted through the rearward slots and emerging 105 through the forward slots to form loops interior to the closure flap and adapted to receive and secure therein an umbrella or other article, the straps having projections thereon adjacent the forward slots preventing forward portions of the straps pulling back through the slots, and means for securing end portions of the respective straps exteriorly to the bag front wall, whereby the closure flap may be secured in closed position in the usual manner and 110 the article secured in the loops in enclosed position within the upper portion of the closure flap.

115 In testimony whereof I have signed this specification this 22d day of June, 1927.

120 WILLIAM H. BEEHLER.
